SWEEPER

Marcus A. Bailey, Tucker, Ga.

Application October 1, 1953, Serial No. 383,478

3 Claims. (Cl. 15—160)

This invention relates to a sweeper, and more specifically provides a sweeper having a pair of adjustable brushes to adjust the width of the effective sweeping path.

An object of this invention is to provide a sweeper having a pair of handles wherein manipulation of the handles causes an adjustment of the width of the sweeping path.

Another object of this invention is to provide a sweeper having a pair of caster rollers thereby facilitating the movement of the sweeper.

A further object of this invention is to provide a sweeper having a pair of angular adjustable brushes and a synchronized linkage system for adjusting each brush.

Yet another object of this invention is to provide a sweeper which may be easily adjusted and propelled to vary the width of the sweeping path.

A still further object of this invention is to provide a sweeper which is simple in construction, easy to operate and adjust and inexpensive to manufacture.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a top plan view of the sweeper of this invention with a portion of the handle members broken away;

Figure 2 is an end view looking from the right hand section of Figure 1 showing the relationship between the sweeper brushes and the operating linkages;

Figure 3 is a transverse, vertical section taken substantially along the junction between the actuating levers and the connecting members;

Figure 4 is a longitudinal, vertical section taken substantially along the longitudinal center line of the sweeper;

Figure 5 is a transverse, vertical section taken substantially along section line 5—5 of Figure 4 showing details of the brush mounting pin; and

Figure 6 is a perspective view of one of the brush members with the trash carrying projection along the top edge thereof.

Referring now specifically to Figure 1 of the drawings, it will be seen that the numeral 10 generally designates the sweeper of this invention having a pair of elongated brushes 12 extending in angular relation to each other and a pair of handle members 14 extending upwardly and rearwardly from the sweeper 10.

The sweeper 10 includes a generally rectangular plate 16 having a pair of depending U-shaped members 18 adjacent one end thereof with one of the U-shaped members 18 located adjacent the side edge of the plate 16 and the other U-shaped member being located adjacent the opposite side edge of the member 16. The U-shaped members 18 rotatably support a pair of rollers or casters 20 on a suitable axle 22. Adjacent the opposite end of the plate 16 is a pair of suitable apertures adjacent each corner receiving a pivotal shaft 24 which is rigidly secured adjacent one end of the brush member 12 and an off-set

2

link 26 is secured to the upper end of the shaft 24 by the use of a suitable set screw 28 and it will be seen that the link 26 is spaced from the upper surface of the plate 16 by a suitable bearing spacer 30. Adjacent the casters 20 and positioned on the upper surface of the plate 16 is a pair of upstanding pins 32 rotatably securing a hub member 34 thereon. The hub member 34 includes a segment gear 36 adjacent the bottom end thereof and an elongated extending lever 38 projecting from the upper edge of the hub 34 and an ear member 40 projecting rearwardly of the hub member 34 and having a suitable aperture therein for receiving a pivot bolt 42 for adjustably securing handle members 14 about the pivot bolt 42 to the extension 40 wherein the handle 14, lever 38 and segment gear 36 are pivotal about the vertical axis formed by the vertical pin 32 and the handle 14 is pivoted about the horizontal axis formed by the pivot bolt 42. A suitable fastening means such as a cotter pin 46 is inserted through the upper end of the vertical pin 32 for securing the hub 34 thereon. As will be seen in Figure 1, there are two vertical pins 32 located adjacent opposite corners of the plate 16 and the handles 14 extend rearwardly therefrom and upwardly inclined to a rubber hand grip portion (not shown). The lever members 38 extend angularly from the hub 34 and project across the plates 16 and cross each other and are pivotally attached to the off-set link 26 by a connecting member 48 which spaces the ends of the levers 38 from the links 26 and completes the linkage connection between the brushes 12 and handles 14. It will be noted that segmental gears 36 mounted on the hub 34 are in meshing engagement and when the hub 34 is pivoted about the pins 32 by moving the handles 14 the gears 36 and the levers 38 are synchronized in their pivotal movement due to the meshing of the segment gears 36. Obviously, the off-set links 26 are moved simultaneously and the brushes 12 are pivoted about the shaft 24 at the same time and through the same number of angular degrees. As best shown in Figure 6, the brush 12 may be provided with a longitudinal extension 50 secured to the upper edge of the brush and projecting upwardly therefrom for moving bulky trash over the surface to be swept. The extension 50 is generally right angular in configuration with one of the legs being short and having key-hole slots 52 therein for receiving screw heads 54 inserted in the upper edge of the brush member 12 thereby fastening the extension to the brush 12 in an obvious manner. The brushes 12 are of a special design for the purpose and having an elongated rigid member with the bristles depending therefrom and presenting a flat sweeping surface. It will be noted that the distance from the under surface of the plate to the bottom of the caster wheels 18 is substantially equal to the distance from the under surface of the plate to the bottom edge of the brushes 12; further, the distance between the upper surface of the plate 16 and the various linkages is substantially equal, thereby providing an easy movement of the lever 38, the off-set link 26 and the connecting member 48.

The operation of the device will be readily understood. The brushes 12 are set in the desired position by operating the handles 14, either by moving them toward each other or away from each other and the sweeper 10 is propelled along the surface to be cleaned. Where the area to be cleaned has various obstructions such as shallow passageway, the brushes 12 may be adjusted to vary the path of sweeping movement by manipulating of the handles 14 thereby effectively cleaning the entire passageway with one operation of the sweeper. Obviously, this device is especially useful in the cleaning of areas having numerous obstructions wherein the sweeper having a stationary brush must be passed along the surface to be cleaned numerous times to efficiently clean the surface, whereas the device of this invention will effectively clean

the surface with only a single cleaning movement. The extension 50 may be placed upon the brush members 12 for effectively cleaning the area of bulky and light trash. The linkage system and gears may be covered with a suitable housing, if so desired, thereby providing a more pleasing appearance and protecting the working mechanism from damage and dust. The various parts of this device may be made of suitable castings such as aluminum for light weight and durability and a housing of cast aluminum may also be provided, however, other materials may be used or employed as desired or may become available. The casters 20 provide an easy propelling support for the sweeper 10 and also provide a pivot point for raising the brushes 12 from the floor and returning the sweeper 10 for a repeat of the sweeping operation. The 15 brushes 12 can be opened to a maximum of 180 degrees and the handles 14 can be pivoted around pivot bolt 42 to a vertical position so that when brushes 12 are opened to 180 degrees and handles 14 are pivoted to vertical position, the entire sweeping instrument can be stored in a space not more than two to three inches wider than the longest dimension of frame 16. The brushes 12 will be so designed that they can be switched from side to side, that is interchangeable from one side to the other, thus when the brush fibers become bent back by forward movement, switching brushes will cause the fibers to be bent forward thereby increasing the efficiency of sweeping and adding life to the brushes.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents

may be resorted to, falling within the scope of the appended claims:

What is claimed as new is as follows:

1. In a sweeper, a rectangular plate having front and rear ends and sides, a pair of caster wheels at the rear end and opposite sides of said plate, a pair of elongated brushes extending forwardly of the front end of the plate and having rear ends pivoted to said front end and opposite sides of the plate for swinging of said brushes laterally with respect to each other, and means for swinging said brushes in synchronism comprising a pair of intermeshing gear segments pivoted on said plate adjacent said rear end and opposite sides of said plate, a pair of rearwardly extending handles on said segments for pivoting the same, a pair of levers on said segments extending forwardly therefrom in crossed relation and swingable oppositely, relatively, by pivoting of said segments, and operating connections between said levers and said brushes.

2. In a sweeper according to claim 1, said operating connections comprising a pair of links fixed to the pivots of said brushes, and a pair of pivoted links connecting said levers to said first named links.

3. In a sweeper according to claim 1, said handles being pivoted on said segments for vertical swinging thereon into different positions.
